Primary Examiner — R. Johnson(74) *Attorney, Agent, or Firm* — Daniel C. Pierron;
Widerman Malek PL(57) **CLAIM**

The ornamental design for a child rolling prevention device, as shown and described.

DESCRIPTION

FIG. 1 is a perspective view of a child rolling prevention device according to the present invention.

FIG. 2 is a right-side elevation view of the child rolling prevention device illustrated in FIG. 1.

FIG. 3 is a front elevation view of the child rolling prevention device illustrated in FIG. 1.

FIG. 4 is a rear elevation view of the child rolling prevention device illustrated in FIG. 1.

FIG. 5 is a bottom view of the child rolling prevention device illustrated in FIG. 1; and,

FIG. 6 is a top view of the child rolling prevention device illustrated in FIG. 1.

The broken lines depict elements of the child rolling prevention device that do not form a claimed feature of the present invention.
